DESIGN FOR A DRAFTING MACHINE

Floyd G. Eubanks, Pasadena, Calif., assignor of forty-seven and one-half per cent to Francis E. Vaughan, Pasadena, Calif., and five per cent to Robert M. McManigal, South Pasadena, Calif.

Application July 29, 1942, Serial No. 107,736

Term of patent 14 years

To all whom it may concern:

Be it known that I, Floyd G. Eubanks, a citizen of the United States, residing at Pasadena, in the county of Los Angeles and State of California, have invented a new, original, and ornamental Design for a Drafting Machine, of which the following is a specification, reference being had to the accompanying drawing, forming part thereof.

Figure 1 is a perspective view of a drafting machine showing my new design.

Figure 2 is an elevational view thereof taken as indicated along the line indicated by the arrow 2.

The dominant features of my design are shown in solid lines on the drawing.

I claim:

The ornamental design for a drafting machine, as shown and described.

FLOYD G. EUBANKS.
